(57) **CLAIM**

The ornamental design for a stethoscope charm, as shown and described.

DESCRIPTION

FIG. 1 is a front view of a stethoscope charm showing my new design;

FIG. 2 is a back view thereof;

FIG. 3 is a right side view thereof;

FIG. 4 is a left side view thereof;

FIG. 5 is a top view thereof;

FIG. 6 is a bottom view thereof;

FIG. 7 is a top view thereof, showing the stethoscope charm in an alternate state; and,

FIG. 8 is a perspective view thereof, showing the stethoscope charm in an alternate state.

The broken lines in FIG. 8 represent environmental subject matter only and form no part of the claimed design.
